UNITED STATES PATENT OFFICE.

ERNEST W. BRACKETT, OF NEWARK, NEW JERSEY, ASSIGNOR TO SPLITDORF ELECTRICAL COMPANY, OF NEWARK, NEW JERSEY.

MAGNETO-MOUNTING.

1,102,385.

Specification of Letters Patent.

Patented July 7, 1914.

Application filed October 28, 1913. Serial No. 797,732.

To all whom it may concern:

Be it known that I, ERNEST W. BRACKETT, a citizen of the United States, resident of Newark, county of Essex, State of New Jersey, have invented certain new and useful Improvements in Magneto-Mountings, of which the following is a specification.

My invention relates particularly to the mounting of a magneto on an internal combustion engine, such as used in automobiles. On certain types of engines of this character, which have the explosive mixtures fired by what is known as the "battery" system, or "vibrating coil" system, it has been found 15 advantageous to substitute a magneto for the above mentioned systems. The method of making such substitution has been found very difficult, and my invention shows the method of making this substitution on cars 20 which are already in service. The application is direct, comparatively simple, and inexpensive. It is more particularly suited to cars of the "Ford" type, which use a "vibrating coil" system ignition. The application 25 of the magneto with its mounting to an engine of this character is shown in the attached drawings and hereinafter described, in which—

Figure 1 shows a plan view of a portion of the engine and magneto with a section 30 through a part of the magneto mounting plate. Fig. 2 shows an end elevation of the engine with the magneto mounted thereon and having a portion of the outer cover 35 plate broken away, to show the method of driving the magneto. Fig. 3 is a view of the mounting plate, which is attached to the engine frame and which also carries the magneto. Fig. 4 is a view of the outer cover 40 plate taken off from the mounting plate. Fig. 5 is a view of the breather cap used to close the oil hole for putting oil into the crank case of the engine.

Referring now to the different figures in 45 which the corresponding numbers relate to corresponding parts, 1 is the engine supported on the frame work 2.

3 is the plate which is attached to the engine crank case and which houses the gears

used for driving the magneto, and which 50 also carries a lug 20, upon which the magneto is mounted. The magneto is attached to a lug 20 by means of the straps 11 and bolt 12. The high tension leads are attached to the distributor of the magneto by the buttons 25 (only 2 are shown in the drawing). From these buttons 25, leads run direct to the spark plugs 26 of the engine 1.

The magneto shaft 15 projects through 60 and into the plate 3, and has mounted thereon, gear wheel 18, held in place by the nut 19. Rigidly fastened to the plate 3 is a stud 14, which carries a gear 17. Mounted on cam shaft 13 of the engine is a gear 16. The three gears, 16, 17 and 18 are constantly 65 in mesh, and as the engine turns, are driven in accordance with the gear reduction, produced by the above mentioned gears.

The plate 3 is attached to the end of the engine crank case by means of bolts 9, passing 70 through the holes 8. Fastened to the outer face of plate 3 by means of screws 5, is a small plate 4, which serves to inclose the gears within plate 3. Integral with the plate 3 is an oil cup 6. The top of the oil cup is bored out to receive a cap 7 which is held in 75 place within the cup by means of the resilient lip 21. Mounted within the cap is a piece of gauze 22 and above this is opening 23. No invention is claimed for this cap 80 shown in Fig. 5, but it is shown for the purpose of illustrating how I am able, by my invention to incorporate a device already in use on engines, into that part of my device which I claim as new. The plate 3 also carries a lug 24, which is used for adjusting the tension of the fan belt used on such automobile engine. The lug 24 is thus incorporated in my device in the same manner 85 that the cup 6 and cap 7 are.

25 is a hole through a boss 26 which extends the entire length of lug 20 for the purpose of supporting a link in the advance rod for advancing and retarding the spark. The advance lever is on the end of the magneto which carries the distributor but is not 90 shown in the drawings.

I have therefore invented a mounting

plate which can be substituted for those now on the "Ford" automobile, and which has integral with it, a lug for carrying the magneto, which lug carries a boss for supporting one of the advance lever members, and the oil cup for oiling the engine, and a lug for adjusting the fan belt at the same time it serves to house the gears, so as to keep them free from dust and dirt and other obstructions.

It will be seen that certain changes can be made in some of the details in my invention shown herein, but I believe these changes come within the scope of the appended claims.

Having thus described my invention, what I claim, is:

1. In a device of the class described, the combination of an engine frame, a driving shaft projecting therefrom, a plate for said engine frame inclosing said driving shaft, said plate having a lug projecting rearwardly away from the face of said plate, a magneto mounted on said lug and having its shaft terminating within said plate, gears within said plate arranged to connect said driving shaft to said magneto shaft, and an auxiliary plate to cover said gears, substantially as described.

2. In a device of the class described, the combination of an engine frame, a driving shaft projecting therefrom, a plate attached to said frame and inclosing said driving shaft, gears inclosed within said plate, a lug integral with said plate, a magneto adapted to be mounted on said lug and driven by said gears and a second plate attached to said first plate to cover said gears, substantially as described.

3. In combination, an internal combustion engine, a magneto for firing fuel in said engine, a plate adapted to be fastened to said engine, means for driving said magneto, said plate carrying said magneto and inclosing said magneto driving means, substantially as described.

4. In combination, an internal combustion engine, a magneto for firing the fuel in said engine, a plate adapted to be fastened to said engine, means for driving said magneto, means for putting oil in the crank case of said engine, said plate carrying both said magneto and oiling means and encompassing said magneto driving means, substantially as described.

5. In combination, an internal combustion engine, a magneto for firing the fuel in said engine cylinders, a plate adapted to be fastened to said engine, means for driving said magneto, means for putting oil into the crank case of said engine, breathing means for allowing the air to pass freely back and forth to the interior of said engine crank case, said plate carrying the

magneto, the oiling and breathing means 65 and encompassing said magneto driving means, substantially as described.

6. In combination, an internal combustion engine, a magneto for firing the fuel in said engine cylinders, a plate adapted to 70 be fastened to said engine, means for driving said magneto, means for putting oil into the crank case of said engine, breathing means for allowing the air to pass freely into and out of said engine crank case, a 75 lug integral with said plate for carrying said magneto, the said oiling means being also integral with said plate and carrying the breathing means, said plate encircling the said driving means, substantially as de- 80 scribed.

7. In combination, an internal combustion engine and means for firing the fuel in said engine cylinders, a plate attached to the said engine and carrying said firing means, 85 a shaft from said engine extending into said plate, a shaft from said firing means, extending into said plate, gear wheels mounted on both said shafts, an intermediate shaft rigidly attached to said plate and carrying 90 a third gear wheel adapted to mesh with the first two mentioned gears, whereby the firing means is driven at the proper speed to fire said engine, substantially as described.

8. In combination, an internal combustion engine and a magneto for firing the fuel within the engine cylinders, a chambered plate having a lug integral therewith for carrying the magneto and a cup also integral with the plate for oiling the engine 100 crank, said cup carrying a breathing device for the engine crank case, a shaft from said engine extending into the chamber of said plate, a shaft from said magneto also extending into the said chamber, a third 105 shaft rigidly connected to said chambered plate, gears adapted to be mounted on said shaft and mesh together, whereby the magneto is driven by said engine, and an auxiliary plate, to cover said chambered plate, 110 substantially as described.

9. In combination, an internal combustion engine, a magneto for firing fuel in said engine, a plate adapted to be fastened to said engine, means for driving said magneto, 115 said plate having a lug for carrying said magneto, said lug carrying means for supporting one of the ignition advance lever members, as described.

10. In combination, an internal combustion engine, a magneto for firing fuel in said engine, a plate adapted to be fastened to said engine, means for driving said magneto, a lug integral with said plate for carrying said magneto, and a boss integral with said lug for supporting a part of the ignition lever members.

11. In combination, an internal combus-

tion engine and means for firing the fuel in said engine cylinders, a plate attached to said engine and carrying said firing means, a shaft from said engine extending into said plate, a shaft from said firing means extending into said plate, means for driving the last mentioned shaft from the first, whereby

the firing means is driven at the proper speed, to fire said engine, substantially as described.

ERNEST W. BRACKETT.
